UNITED STATES PATENT OFFICE.

CHARLES W. BECK, OF NEW YORK, N. Y.

ACETYLENE-GAS GENERATOR.

No. 892,573.

Specification of Letters Patent.

Patented July 7, 1908.

Application filed October 26, 1904, Serial No. 230,002. Renewed November 8, 1907. Serial No. 401,328.

To all whom it may concern:

Be it known that I, CHARLES W. BECK, a citizen of the United States, residing at Manhattan, city, county, and State of New York, 5 have invented certain new and useful Improvements in Acetylene-Gas Generators, of which the following is a specification, reference being had therein to the accompanying drawings, in which—

10 Figure 1 is a vertical sectional view on the line I—I of Fig. 2, of the generator in the form of a vehicle lamp; Fig. 2 a side elevation thereof; Fig. 3 a vertical central section showing the feed mechanism depressed; Fig. 4 a horizontal sectional view taken on the line IV—IV of Fig. 1 and showing the flexible split diaphragm; and Fig. 5 a similar view of the water holder.

15 The main objects of this invention are to produce a carbid feed generator or lamp of simple construction especially adapted for use upon vehicles; to provide such a generator with a tubular feed device through which carbid may be fed to the water holder; to provide means to prevent water splashing up into the feed mechanism; to form a protected water compartment to receive the carbid; and to provide means for cleaning the interior of said tubular feed plunger during each reciprocation thereof, said cleaning device forming a flexible liquid-tight closure valve which prevents the passage of carbid through the plunger except when said plunger is depressed, and, when the plunger is raised, seals the water and carbid chambers and prevents entrance of moisture into the carbid chamber.

Other important objects and advantages will appear hereinafter.

40 Referring to the various parts by numerals 1 designates the water holder, and 2 the carbid holder, this latter part carrying the feed mechanism. The lower part of the carbid holder is contracted, as at 5, to reduce the gas space therein and to give it a pleasing appearance; and to the lower end of this reduced part is secured a threaded ring 3 which engages a correspondingly threaded ring 4 permanently secured to the top of the water holder and detachably connects the two parts. Across the upper end of the carbid holder a suitable distance below its top is rigidly secured a horizontal partition 6; and just above the contracted part 5 is rigidly secured the downward and inward in-

clined bottom 7, the inner end of this bottom extending downward vertically to form the flange 8. The space below the bottom 7 forms a gas chamber.

Within the compartment 9 formed above the partition 6 is arranged a flexible gas bag 10 which is formed with a central aperture in its lower wall which registers with a corresponding aperture in the partition. Extending through these registering apertures 65 is a threaded ring 11 provided at its upper end with a horizontal flange 12 which rests on the inner surface of the lower wall of the gas bag. Secured to the lower end of this threaded ring or nipple is the upper threaded 70 end of a depending housing 13 which bears against the under side of the partition 6.

Secured to the upper wall of the gas bag is a depending tubular valve rod 14 extending centrally through the housing 13, its lower 75 end projecting below said housing and carrying the outward and downward extending arms 15. To the lower ends of these arched arms is rigidly secured, or formed integral therewith, a tubular feed plunger 16, said 80 plunger being concentric with the flange 8 of the bottom and in substantially the same horizontal plane. This plunger is threaded exteriorly and screwed on its upper end is a ring 17 to which the inner edge of a ring-like 85 flexible diaphragm 18 is permanently secured. The outer edge of this diaphragm is permanently secured to the exterior of a ring 19 which is secured to the exterior of the flange 8. 90

Within the tubular valve rod is loosely mounted a bar 20 which is provided at its lower end with a disk 21 of rubber or other suitable material, whose periphery is flexible and is adapted to fit closely within the tubular feed plunger and to serve as a liquid-tight closure therefor and as a means for cleaning same as said plunger is reciprocated. The rod 20 within the tubular housing is provided with suitable collars 20^a to hold it centrally therein, and with the lateral finger 22 which extends outward through a slot 23 in the tubular valve rod and is adapted to engage stops 24 formed on the interior of the tubular housing, one of said stops being located a short 105 distance above the other to permit the closure device to have a short vertical movement with the feed plunger.

Secured to the upper end of the valve rod is one end of a coiled contractile spring 25, 110

the lower end of said spring being connected to a sleeve 26 which is provided at its lower end with an outward extending flange, said flange engaging below the reduced part 27 of the housing. The action of the spring 25 is to normally collapse the gas bag and to depress the feed plunger sufficiently to carry its upper edge below the closure and cleaning device 21, to thereby permit carbid to flow down through said plunger. The pressure of the gas in the gas bag will extend the spring 25 and lift the plunger until the arms 15 contact with the lower end of the housing 13. During the upward movement of the 10 plunger the finger 22 of the closure rod will contact with the upper stop 24 of the housing and prevent a further upward movement of the rod and cause the disk 21 to enter the feed plunger and clean the same and at the same time prevent the passage of carbid 15 therethrough until the plunger is again lowered by the spring 25 collapsing the gas bag. During the first part of the descent of the plunger the closure disk moves therewith 20 until finger 22 contacts with lower stop 24. 25

Secured to the lower end of the tubular feed plunger is a depending tubular spreader 29, whose lower end extends near to the bottom of the gas chamber of the carbid holder. 30 Extending below the ring 3, a suitable distance, so as to project down into the water holder when the parts are assembled, is an extension 30 of the gas chamber. Secured across the lower end of this extension by 35 means of suitable clamping rings, is a horizontal flexible diaphragm 31 formed of rubber or other suitable material. This diaphragm is formed of a plurality of flaps which normally lie in a horizontal position and form a yielding closure, said flaps being 40 formed by slitting the diaphragm radially, as at 32. This diaphragm is adapted to be engaged by the tubular spreader when the feed plunger is depressed, said spreader forcing the flaps downward so that the carbid falling through the feed plunger may pass 45 down through the spreader 29 below the diaphragm and into the water. As soon as the spreader is raised by the pressure of the gas 50 in the gas holder the flaps of the diaphragm will return to their normal position, closing the lower end of the gas chamber and preventing the water being splashed therein by reason of the jolting or vibrating of the vehicle on which the lamp or generator may be 55 placed. By employing the tubular spreader the carbid is guided in its descent and its passage down through the split diaphragm is assured. Openings 30^a are formed in the extension 30 to permit any gas which may accumulate in the water holder to pass into the gas space of the carbid holder. When the carbid holder is secured to the water holder the split diaphragm 31 is practically at the 60 normal water level in the water holder the 65

said diaphragm practically resting on the top of the water.

By placing the split diaphragm 31 near the normal water level in the generating chamber or water holder the sections thereof, 70 formed by splitting the diaphragm as described, will be forced down into the water when the feed plunger is depressed. In their depressed position they form a compartment within the water which will be protected to a large extent from the agitation or 75 movement of the water in the balance of the water holder. This is of great advantage in that it aids materially in preventing water splashing up to the feed mechanism. It will 80 also be noted that the tubular spreader will enter the water below the diaphragm and form still another or inner protected compartment in which the water will be comparatively free from motion. It is essential 85 that the water directly below the feed mechanism be comparatively motionless during the feeding of carbid.

In the water holder axially in line with the feed plunger is mounted a vertical post 33. 90 Adapted to slide on this post is a float 34 whose upper surface inclines outward and downward. Secured to this float slightly above its upper surface are a series of horizontal screens 35, said screens being parallel 95 with each other and separated slightly. They are supported on the top of the float by means of small arms or posts 36. Secured to the float and surrounding the screens are a plurality of deflectors 37 which 100 incline outward and downward. The upper edge of the upper deflector is above the upper screen and bears directly against the under side of the diaphragm 31 and serves to normally hold the flaps of the diaphragm in 105 a horizontal position.

The float by raising the deflectors and screens assists the flaps of the screen to return to their normal horizontal position. It is obvious that when the tubular spreader depresses the members of the diaphragm it will also force downward the screens and the float and that when the gas pressure raises the feed plunger and the spreader the float will carry the screens upward. This vertical movement of the screens will cause all 110 the lime to pass downward through them into the water holder.

The lower edge of the upper deflector overlaps the upper edge of the lower deflector, 120 the lower deflector extending inside of the upper one, as shown. It is obvious that the screens will, to a great extent, prevent water splashing up into the spreader, and it is the purpose of the deflectors to prevent water 125 splashing on or through the screens, said deflectors forming practically a protected compartment around the screens. It is of course necessary that suitable water-ways or 130 passages be formed between the float and the

lower deflector and between the adjoining ends of the deflectors in order that during the reciprocation of the float water may pass freely between the deflectors and screens to wash out the lime. It is, of course, obvious that during the violent shaking which the lamp will receive when in use, the water will, to a certain extent, be forced between the deflectors and through the screens. This movement of the water will materially assist in keeping the screens and deflectors free of lime and residue. It will thus be seen that a small protected water compartment will be formed at each descent of the spreader and that the carbid will be delivered into this compartment. It will also be noted that this compartment is destroyed as soon as sufficient gas is generated to inflate the gas holder and that thereafter the agitation of the water in the water holder will clean the screens and deflectors and that a fresh supply of water will be in the protected compartment at the next descent of the spreader.

The operation of the apparatus may be briefly described as follows:—In starting the generation of gas the stop nut 43 will be run up the screw 44 sufficiently to permit the spring 25 to depress the feed plunger below the closure device 21 and to carry the tubular spreader down into contact with the split diaphragm 31. The spreader will depress the members of the diaphragm and separate them to form a protected water compartment, as shown in Fig. 3. Carbid will flow through the plunger and the spreader device and drop into the water in the protected compartment. The gas generated will flow upward through the spreader and plunger into the carbid holder and thence through the filter 45 into the gas bag 10. The pressure of gas therein will, when it overcomes the tension of the spring 25, raise the plunger and spreader device until the closure device 21 enters the plunger and stops the flow of carbid. When the spreader has been raised out of the water in the water holder and the closure device has entered the feed plunger there will be an equalization of gas pressure throughout the apparatus below the feed plunger. When the gas pressure in the gas holder 10 has been sufficiently reduced, the spring 25 will again depress the plunger and spreader. Gas passes from the top of the carbid holder through the filter 41, into pipe 39 and thence to the burner.

The burner is located within a suitable reflector head 38 and is connected by a pipe 39 to the interior of the carbid holder, said pipe being carried by the plug 40 which is screwed into the side of the carbid holder. Surrounding this pipe within the carbid holder is a filter 41 of felt or other fibrous material. The screw plug 40 is of such size that by removing it from the casing the

filter may be withdrawn from the carbid holder. The pipe 39 is formed in two sections which are connected by a coupling 42, in order that said sections may be disconnected when the carbid hopper is removed from the water holder.

When it is desired to stop the generation of gas the feed plunger is raised by means of a thumb nut 43, which bears against the top of the carbid holder and is threaded on a screw 44 connected to the feed plunger. When it is desired to start the generation of gas it is simply necessary to run the thumb nut up the screw 44 and permit the spring 25 to collapse the gas bag and depress the feed plunger.

Near its upper end the housing 13 is perforated and over these perforations is secured a fibrous filter 45, this filter being spaced out from the exterior of the housing 85 by means of a spacing ring 46 secured to the housing below the perforations. The purpose of this filter is to prevent lime and other impurities being carried into the gas bag by the gas.

I desire it understood that I do not wish to limit myself to the precise construction and arrangement of parts herein described as many changes may be made therein without departing from the scope of the invention.

Having thus described my invention what I claim as new and desire to secure by Letters Patent, is:—

1. An acetylene gas generator comprising a water holder, a carbid holder provided with a discharge opening in its bottom, a tubular feed plunger working in the discharge opening and through which carbid flows from its upper to its lower end, means operated by gas pressure for reciprocating said plunger to control the flow of carbid therethrough, and means for cleaning the interior of said feed plunger as the same reciprocates, said means fitting the interior of said feed plunger during a portion of its movement.

2. An acetylene gas generator comprising a water holder, a carbid holder provided with a discharge opening in its bottom, a tubular feed plunger working in the discharge opening and through which carbid flows from its upper to its lower end, means for reciprocating said plunger to control the flow of carbid therethrough and a closure device adapted to fit within said plunger as the same reciprocates to stop the flow of carbid, said closure device engaging the plunger during a portion of its movement.

3. An acetylene gas generator comprising a water holder, a carbid holder provided with a discharge opening in its bottom, a tubular feed plunger working in the discharge opening and through which carbid flows from its upper to its lower end, and a flexible closure device adapted to enter the

plunger as the same is raised to stop the flow of carbid therethrough and to clean the interior thereof.

4. An acetylene gas generator comprising a water holder, a carbid holder formed with a discharge opening, a tubular feed plunger, a flexible diaphragm connected to said plunger and to the bottom of the carbid holder and closing the discharge opening,

10 means for reciprocating the plunger to control the flow of carbid therethrough, and a closure device adapted to fit within the plunger as the same is raised to stop the discharge of carbid.

15 5. An acetylene gas generator comprising a water holder, a carbid holder formed with a discharge opening, a tubular feed plunger working through said opening, a flexible diaphragm secured to the plunger and to the 20 bottom of the carbid holder, means for reciprocating the plunger to control the flow of carbid, and means for cleaning the interior of the said feed plunger as same reciprocates.

25 6. An acetylene gas generator comprising a water holder, a carbid holder formed with a discharge opening at its bottom, a tubular feed plunger working through said opening a flexible diaphragm connected to said feed 30 plunger and to the bottom of the carbid holder, means operated by variations in gas pressure to reciprocate said plunger, and a flexible disk closure device adapted to enter the plunger when the same is raised to stop 35 the flow of carbid and clean the interior of the plunger.

40 7. In an acetylene gas generator a diaphragm forming a support upon which the carbid is adapted to rest and provided with a permanently open feed passage therethrough, feed mechanism operated by changes in gas pressure and connected to said diaphragm to bodily reciprocate a portion around the feed opening whereby the flow of carbid 45 through the feed opening is controlled, and a closure device adapted to enter said feed opening when the diaphragm is raised to stop the discharge of carbid.

50 8. In an acetylene gas generator a diaphragm formed with a feed opening, mechanism operated by changes in gas pressure to bodily move that portion of the diaphragm surrounding the feed opening whereby the flow of carbid through the feed opening is 55 controlled, and a closure device adapted to enter the feed opening during the reciprocation of the diaphragm to stop the flow of carbid therethrough.

60 9. An acetylene gas generator comprising a water holder, a carbid holder, a tubular feed plunger at the bottom of the carbid holder, means for reciprocating said plunger to control the flow of carbid, and a relatively 65 stationary device for cleaning the interior of said feed plunger as the same reciprocates.

10. An acetylene gas generator comprising a water holder, a carbid holder, a tubular feed plunger at the bottom of the carbid holder, means for reciprocating said plunger to control the flow of carbid, and a relatively 70 stationary device provided with a yielding periphery adapted to enter the feed plunger as the same reciprocates to clean the interior of said plunger and stop the flow of carbid.

11. An acetylene gas generator comprising a water holder, a carbid holder above the water holder, an expansible gas bag near the top of the carbid holder, a tubular feed plunger at the bottom of the carbid holder, a valve rod connecting said tubular plunger to the 80 movable wall of the gas holder, a closure device supported by said valve rod, said closure device being adapted to enter the plunger when the same is raised to stop the flow of carbid therethrough, and means whereby 85 the plunger may move independent of the closure device.

12. An acetylene gas generator comprising a water holder, a carbid holder above the water holder, an expansible gas bag near the 90 top of the carbid holder, a tubular feed plunger at the bottom of the carbid holder, a valve rod connecting said tubular plunger to the movable wall of the gas holder, a closure device supported by said valve rod, 95 said closure device being adapted to enter the plunger when the same is raised to stop the flow of carbid therethrough, and means whereby the closure device may move a short distance with the plunger and will then 100 be arrested and held stationary during the remainder of the movement of the plunger.

13. An acetylene gas generator comprising a water holder, a carbid holder, a tubular feed plunger in communication at its upper 105 end with the bottom of the carbid holder, means for reciprocating said plunger to control the flow of carbid, a relatively stationary device for cleaning the interior of said feed plunger as the same reciprocates, a yieldable 110 diaphragm below the plunger and closing the passage from the carbid holder to the water holder, and means carried by the tubular feed plunger for moving a part of said diaphragm to permit the carbid to pass into the 115 water holder.

14. An acetylene gas generator comprising a water holder, a carbid holder, a tubular feed plunger in communication at its upper end with the bottom of the carbid holder, means for reciprocating said plunger to control the flow of carbid, a relatively stationary device for cleaning the interior of said feed plunger as the same reciprocates, a split 120 yieldable diaphragm below the plunger and closing the passage from the carbid holder to the water holder, and means carried by the tubular feed plunger for moving a part of said diaphragm to permit the carbid to pass 125 into the water holder.

15. An acetylene gas generator comprising a water holder, a carbid holder, a tubular feed plunger in communication at its upper end with the bottom of the carbid holder, 5 means for reciprocating said plunger to control the flow of carbid, a relatively stationary device for cleaning the interior of said feed plunger as the same reciprocates, a yieldable diaphragm below the plunger and closing the 10 passage from the carbid holder to the water holder, and a tubular spreader carried by the feed plunger for moving a part of said diaphragm to permit the carbid to pass into the water holder, said spreader being open at its 15 ends to permit the carbid to flow therethrough into the water holder below the split diaphragm.
16. In an acetylene generator the combination with a generating chamber, of a flexible diaphragm located substantially at the 20 level of the water in the generating chamber and formed of a plurality of sections adapted to be forced downward into the water, for the purpose set forth, and a tubular spreader device adapted to engage the sections of the diaphragm at separated points to depress the same.
17. In a carbid feed acetylene generator, the combination with a generating chamber 30 provided with an inlet passage through which carbid is fed, of a diaphragm-like screen extending across said passage substantially at the water level in the generating chamber, said screen being formed of a plurality of sections adapted to be forced downward into the water to permit the carbid to pass therethrough and to thereby form a protected compartment in the water to receive the carbid and then automatically return to 40 their normal horizontal position to prevent the water splashing up to the feed mechanism, and a tubular spreader device adapted to engage the diaphragm sections at separated points to depress the same.
45. 18. In an acetylene gas generator the combination with a generating chamber, a feed mechanism operating in response to changes in gas pressure to feed carbid to said generating chamber, a diaphragm-like screen located at the level of the water in the generating chamber and formed of a plurality of flexible sections which normally close the entrance to the generating chamber, a tubular spreader device moved by the feed mechanism and adapted to engage the diaphragm sections at separated points and depress them 55 during the feeding of carbid.
19. An acetylene gas generator comprising a water holder, a carbid holder, a feed mechanism, a flexible normally closed diaphragm between the water holder and the feed mechanism, means carried by the feed mechanism to open the diaphragm when the carbid is fed, and a vertically movable screen below 60 the normally closed diaphragm and adapted to be depressed when said diaphragm is opened, and means yieldably supporting said screen.
20. An acetylene gas generator comprising a water holder, a carbid holder, a feed mechanism, a flexible normally closed diaphragm below the feed mechanism and at the normal water level in the water holder, means carried by the feed mechanism to depress the diaphragm and open it when feeding carbid, 70 a float within the water holder directly below the diaphragm, a screen carried by said float, between the float and the diaphragm.
21. An acetylene gas generator comprising a water holder, a carbid holder, a feed mechanism, a flexible normally closed diaphragm below the feed mechanism and at the normal water level in the water holder, means carried by the feed mechanism to depress the diaphragm and open it when feeding carbid, 80 a float within the water holder directly below the diaphragm, a screen carried by said float between the float and the diaphragm, a plurality of downwardly enlarging deflectors carried by the float and surrounding the screen. 90
22. An acetylene gas generator comprising a water holder, a carbid holder, a feed mechanism, a split diaphragm at the normal water level in the water holder, a tubular spreader carried by the feed mechanism and adapted 95 to depress and open the diaphragm directly below the diaphragm, a float in the water holder, and a screen carried by said float, between the float and the diaphragm.
23. In an acetylene gas generator the combination of a generating chamber provided with an inlet through which carbid is fed, a flexible normally closed screen extending across said inlet substantially at the water level in the generating chamber, a feed mechanism operating in response to changes in gas pressure to feed carbid, and a tubular spreader moved by said feed mechanism and adapted to engage the screen sections and force them downward into the water in the 100 generating chamber during the feeding of carbid.
24. A carbid feed acetylene generator comprising a carbid holder, a water holder, a feed mechanism acting in response to changes in gas pressure, means actuated by said feed mechanism to form a small protected water compartment in the main water holder having a perforated bottom wall and adapted to receive each charge of carbid as 115 it is dropped.
25. A carbid feed acetylene generator comprising a carbid holder, a water holder, a feed mechanism acting in response to changes in gas pressure, means actuated by the feed mechanism to form a temporary and collapsible supplemental protected water compartment in the main water holder to receive each deposit of carbid, and consisting of side and bottom walls. 125

26. A carbid feed acetylene generator comprising a carbid holder, a water holder, a feed mechanism acting in response to changes in gas pressure, means actuated by the feed mechanism to form a protected water compartment in the water holder, said compartment having movable sides and a perforated movable bottom, and means to collapse and destroy said compartment when the feeding of carbid is stopped.

27. A carbid feed acetylene gas generator comprising a water holder, a feed mechanism acting in response to changes in gas pressure, a float in the water holder and adapted to be depressed by the feed mechanism and means carried by said float to form a protected water compartment which is in communication with the main water holder.

28. A carbid feed acetylene generator comprising a carbid holder, a water holder, a feed mechanism acting in response to changes in gas pressure, means within the main water holder to form a supplemental movable water compartment to receive carbid as it is dropped, said compartment consisting of side and bottom walls, said supplemental compartment being in communication through its side wall and bottom with the main water holder, the walls of the supplemental compartment being arranged to prevent the water in the main water holder agitating the water in the supplemental compartment when the lamp is vibrated.

29. A carbid feed acetylene gas generator comprising a carbid holder, a water holder, a pressure-controlled feed mechanism, a float within the water holder, downward and outward inclined shields carried by said float, the adjoining ends of said shields overlapping one within the other, and means whereby the feed mechanism will depress said float and said shields will form the side walls of a protected water compartment.

30. A carbid feed acetylene gas generator comprising a carbid holder, a water holder,

a pressure - controlled feed mechanism, a float in the main water holder, downwardly and outwardly inclined shields carried by said float, the upper end of one shield extending into the shield above, screens within said shields and directly below the feed mechanism, and a tubular device carried by the feed mechanism and adapted to depress the float during the feeding of carbid.

31. A carbid feed acetylene gas generator comprising a carbid holder, a water holder, a pressure controlled feed mechanism, a float in the main water holder, downwardly and outwardly inclined tubular open-ended shields carried by said float, the upper end of one shield extending into the shield above, screens within said shields and a tubular device carried by the feeding mechanism and adapted to fit within the uppermost shield and to depress the float during the feeding of carbid.

32. A carbid feed acetylene generator comprising a carbid holder, a water holder, a feed mechanism acting in response to changes in gas pressure, means actuated by said feed mechanism to form a protected water compartment in the main water holder having a bottom wall and adapted to receive each charge of carbid as it is dropped.

33. A carbid feed acetylene gas generator comprising a carbid holder, a water holder, a feed mechanism acting in response to changes in gas pressure, a depending part carried by the feed mechanism and extending below the carbid holder, and means actuated by said depending part to form a temporary, partially closed well within the water holder during the feeding operation and when the feed mechanism is depressed.

In testimony whereof I hereunto affix my signature in the presence of two witnesses this 7th day of October 1904.

CHARLES W. BECK.
